UNITED STATES PATENT OFFICE.

CLAUS P. CHRISTENSEN, OF PETALUMA, CALIFORNIA, ASSIGNOR OF ONE-HALF TO
H. P. VOGENSEN, OF PETALUMA, CALIFORNIA.

ELECTRIC DRIVING PUMP-JACK.

1,401,042.

Specification of Letters Patent. Patented Dec. 20, 1921.

Application filed September 8, 1920. Serial No. 408,907.

To all whom it may concern:

Be it known that I, CLAUS P. CHRISTENSEN, a citizen of the United States, residing at Petaluma, in the county of Sonoma and State of California, have invented certain new and useful Improvements in Electric Driving Pump-Jacks, of which the following is a specification.

My invention is an improved pump jack for use with reciprocating-rod pumps and it especially has for its object to provide a simple and compact arrangement whereby an electric drive motor may be sustained on the drive head base, as well as the power translating and transmitting mechanism, the said transmitting and translating mechanism being itself of a special design and constitutes one of the principal features of the present invention.

Another object is to provide a worm-drive for the master gear which carries the power applying crank element, a gear on which the crank element coöperates with a fixed gear member or geared track and has a crank co-operative with the reciprocating head-rod to translate the rotary motion of the motor into reciprocating motion in the pump head-rod, thereby transmitting power to the reciprocating rod of the pump.

Another object is to provide for running the gearing and reciprocating connecting rod in oil, in a manner to eliminate oil leakage while maintaining sufficient lubrication of the moving surface.

In its general nature, the invention resides in the provision of a peculiar head base on which the electric motor is mounted and on which the power transmitting and translating mechanism is located; the power transmitting and translating mechanism comprises a driving worm coupled to the motor shaft and meshing with a master worm gear journaled on a sleeve bearing in the housing, which contains the gears; to the master gear a crank disk with a shaft and thrust bearing is secured to the master worm gear to turn with it and has a crank on which is mounted a crank-pinion whose crank is coupled with the reciprocating pump rod by

means of a connecting rod and head rods, the crank-pinion meshing with a fixed gear or geared track to cause the pinion to impart rectilinear motion to the connecting rod,

means being provided for effectually leading lubricant to the several bearing surfaces. 55

In its more subordinate nature, the invention includes those novel features of construction, combination and arrangement of parts, all of which will be first fully described and then be specifically pointed out 60 in the appended claims, reference being had to the accompanying drawings, in which:

Figure 1 is a front elevation of the invention.

Fig. 2 is a vertical cross section on the line 65 2—2 on Fig. 1.

Fig. 3 is a vertical longitudinal section on the line 3—3 on Fig. 2.

Fig. 4 is a top plan view of the invention.

Fig. 5 is a rear elevation of the gear 70 housing.

Fig. 6 is a front elevation of the gear mechanism, the cover and connecting rod being removed.

Fig. 7 is a vertical cross section of the gear 75 housing, *per se*, the cover being removed.

In the drawings in which like numerals of reference designate like parts in all of the figures, 1 represents the head base of the pump which is adapted to be secured in any 80 suitable manner at the top of the well and on which is mounted the drive motor and the power transmitting and translating mechanism.

The base 1 is provided with a downward 85 extension 2 having a chamber provided with a water inlet 4 and an outlet 5.

6 designates a cover which is provided with a gland or stuffing box 7 through which the pump rod 3 passes, the stuffing box 7 90 being adjustable by means of studs and nuts 8.

The rod 3 is secured by nuts 10 to a cross head 9 to which the head-rods 11 are fastened, the rods 11 passing through bearing 95 bushings 12 in the cover 48 of the housing 17, the housing 17 being fastened to the head base 1 by bolts 18, as shown.

The head rods 11—11 are secured by nuts 13 to a cross head 14 which is itself secured 100 by nuts 15 to the connecting rod 16.

17 designates the gear casing which is provided with anti-friction bearings 19 for the worm 20.

The housing is bored through to admit the 105 worm 20 and one end of the boring is closed

by a cap 47, while the other end is closed by a cap with stuffing box 24, through which the worm shaft 21 projects and is coupled at 22 to the shaft of the electric motor 23.

5 The housing 17 has a bearing boss 25 on which the master worm gear 26 is journaled, the bearing surface of the gear 26 being lined with a suitable bearing metal and the gear being provided with oil leads 35 for 10 purposes of lubrication.

The master gear 26 is recessed or counter-bored at 27 to receive the crank disk 28 whose hub 30 is adapted to enter the bore of the bearing boss 25 and which is adapted to 15 be secured in place by a stud 31 and bolt 32 with washer 33, an anti-friction and thrust bearing 34 being provided as best shown in Fig. 2 of the drawings.

This holds the disk 28 in place and also 20 serves to hold the gear 26 in proper position on the bearing 25, a cap being provided over the end of the stud 31, as shown, to effect an oil tight closure of the casing.

The disk 28 has a crank pin 36 provided 25 with suitable oil leads 37 bored to receive a screw 40 which secures the crank pinion 41 in place through the medium of a cap 39, the crank 36 being chambered to provide 30 an oil pocket 38 and itself being provided with oil leads 37 to the bearing surfaces, as best shown in Fig. 2.

The screw 40 is also provided with an oil lead 44 entering through the head and discharging into the chamber 38.

35 The gear 41 has an extension 42 carrying a crank pin 43 on which the lower end of the connecting rod 16 is mounted.

45 is an oil drain from the casing 17. Through this opening 45 oil may be admitted to or removed from the casing, as 40 desired.

49 designates a fixed gear for a geared track which is insertible into the housing and secured to the same by screw bolts 50 which fasten the cover to the housing.

The geared track 49 is interrupted at 55 diametrically opposite places 51 in vertical alignment to receive the crank extension 42 of the crank pinion 41, as the crank pinion 50 is turned through meshing with the geared track, thus the axis of the crank 43 will travel vertically up and down along the diameter of the geared track, passing through the interrupted portions 51 and 55 thereby imparts a rectilinear reciprocating motion to the connecting rod 16, to which motion is, in turn, communicated to the pump rod, as will be clearly understood by those skilled in the art.

60 From the foregoing, it will be noted that with my arrangement, ample provision is made for the lubrication of moving surfaces; a simple, compact and rugged gearing is provided which can be mounted on the base 85 or removed therefrom as a unit and in which

the motive power is directly mounted on the base as a separate unit from the gearing.

While I have illustrated an electric motor as the prime mover, it is clear that other motive powers may be utilized, if desired.

The provision of the opening in the housing cover through which the connecting rod 16 reciprocates, at the highest point or level of the casing, prevents oil leakage from the casing through the opening in which the 75 rod reciprocates, thus rendering the gearing more efficient in its use of lubricant.

Furthermore, by guiding the pump rod 3 in a bearing 6-7 close to but below the gearing and guiding the reciprocating rod 16 in a bearing at the top of the gearing housing with the rod cross head and head rod connections between the pump rod 3 and connecting rod 16, whipping of the rods, with consequent wear on the reciprocating 85 bearing surfaces, is practically eliminated.

From the foregoing description taken in connection with the accompanying drawings, it is thought the operation and advantages of my invention will be readily understood by those skilled in the art.

What I claim is:

1. In a pump jack, a base having a guide for the pump rod, a driving motor mounted on the base, a power transmitting and translating mechanism mounted on the base and coupled to said motor and having provision for coupling to the pump rod, said transmitting and translating mechanism comprising a housing having a cover, a driving worm journaled in bearings in said housing and coupled with said motor, a master worm gear mounted in said housing and meshing with said worm, a crank member carried by said master worm gear, a connecting rod 100 mounted in said cover and means for translating the rotary motion of said crank member into reciprocating motion in said connecting rod.

2. In a pump jack, a base having a guide for the pump rod, a driving motor mounted on the base, a power transmitting and translating mechanism mounted on the base and coupled to said motor and having provision for coupling to the pump rod, said transmitting and translating mechanism comprising a housing having a cover, a driving worm journaled in bearings in said housing and coupled with said motor, a master worm gear mounted in said housing and meshing 115 with said worm, a crank member carried by said master worm gear, a connecting rod mounted in said cover and means for translating the rotary motion of said crank member into reciprocating motion in said connecting rod, said last named means comprising a pinion journaled on said crank member and itself having a crank to which said connecting rod is joined, and a stationary 120 track gear with which said pinion meshes.

3. In a pump jack, a power transmitting and translating mechanism comprising a casing having a sleeve bearing, a master gear journaled on said bearing, a crank disk having a hub journaled in said sleeve bearing, a thrust bearing and means coöperative with said crank disk to hold said disk, said master gear and said thrust bearing in place, a crank-pinion journaled on the crank of said crank disk, means holding said pinion in place, a fixed gear-track with which said pinion meshes, a connecting rod journaled on the crank of said pinion, said casing having an opening through which said connecting rod passes. 40
- 5 4. In a pump jack, a power transmitting and translating mechanism comprising a casing having a sleeve bearing, a master gear journaled on said bearing, a crank disk having a hub journaled in said sleeve bearing, a thrust bearing and means coöperative with said crank disk to hold said disk, said master gear and said thrust bearing in place, a crank-pinion journaled on the crank of said crank disk, means holding said pinion in place, a fixed gear-track with which said pinion meshes, a connecting rod journaled on the crank of said pinion, said casing having an opening through which said connecting rod passes. 45
- 10 5. In a pump jack, a power transmitting and translating mechanism comprising a casing having a sleeve bearing, a master gear journaled on said bearing, a crank disk having a hub journaled in said sleeve bearing, a thrust bearing and means coöperative with said crank disk to hold said disk, said master gear and said thrust bearing in place, a crank-pinion journaled on the crank of said crank disk, means holding said pinion in place, a fixed gear-track with which said pinion meshes, a connecting rod journaled on the crank of said pinion, said casing having an opening through which said connecting rod passes. 50
- 15 6. In a pump jack, a power transmitting and translating mechanism comprising a casing having a sleeve bearing, a master gear journaled on said bearing, a crank disk having a hub journaled in said sleeve bearing, a thrust bearing and means coöperative with said crank disk to hold said disk, said master gear and said thrust bearing in place, a crank-pinion journaled on the crank of said crank disk, means holding said pinion in place, a fixed gear-track with which said pinion meshes, a connecting rod journaled on the crank of said pinion, said casing having an opening through which said connecting rod passes. 55
- 20 7. In a pump jack, a power transmitting and translating mechanism comprising a casing having a sleeve bearing, a master gear journaled on said bearing, a crank disk having a hub journaled in said sleeve bearing, a thrust bearing and means coöperative with said crank disk to hold said disk, said master gear and said thrust bearing in place, a crank-pinion journaled on the crank of said crank disk, means holding said pinion in place, a fixed gear-track with which said pinion meshes, a connecting rod journaled on the crank of said pinion, said casing having an opening through which said connecting rod passes. 60
- 25 8. In a pump jack, a power transmitting and translating mechanism comprising a casing having a sleeve bearing, a master gear journaled on said bearing, a crank disk having a hub journaled in said sleeve bearing, a thrust bearing and means coöperative with said crank disk to hold said disk, said master gear and said thrust bearing in place, a crank-pinion journaled on the crank of said crank disk, means holding said pinion in place, a fixed gear-track with which said pinion meshes, a connecting rod journaled on the crank of said pinion, said casing having an opening through which said connecting rod passes, a shaft having a gear 65
- 30 connection with said master gear journaled in said casing and projecting to the outside of the same, said casing having a packing gland through which said shaft projects, said casing adapted to contain lubricant, 70
- 35 said master gear having oil leads to convey the lubricant to the bearing surface of said sleeve bearing, said means which holds the crank pinion on the disk crank having provision for leading oil to the bearing surface of the disk crank substantially as shown and described. 75

CLAUS P. CHRISTENSEN.
